UNITED STATES PATENT OFFICE.

WILLIAM S. SCHOFIELD, OF PHILADELPHIA, PENNSYLVANIA.

SEPARATOR.

Application filed April 10, 1926. Serial No. 101,054.

My invention relates to separators and is especially adapted for use in textile mills where the stock is blown through pipes from one part of the mill to another part. The stock is usually a mixture of fibers or groups of fibers, of different gravity or a mixture of coarse and fine fibers, or a mixture of fibers or groups of fibers differing in both gravity and bulk. When this mixed stock is discharged from the pneumatic conveyor it is usually discharged into a bin to prevent its being widely scattered by the force of the air current coming from the conveyor pipe. In the bin the stock, instead of settling in a cone-shaped pile, is blown to the periphery of the bin leaving a cone-shaped space in the center of the bin with the apex of the cone downward. The heavier and coarser constituents of the stock settle at or near the bottom of the bin while the lighter and finer constituents are blown upward and gather about the interior wall of the bin and above the heavier and coarser constituents. This produces a non-uniform mixture of the stock which is highly undesirable. To overcome the separating tendency the usual practice is to station a man in the bin to agitate the stock by hand. This is a highly disagreeable job and the results are far from satisfactory. Furthermore the stock has to be removed from the bin before it can go to the next operation. This consumes time and adds to the expense.

The object of my invention is to provide automatic means for separating the air current from the stock as it is discharged from the conveyor thereby permitting the stock to be discharged where it is wanted, without being injuriously affected by the air current, thereby dispensing with the bin and the man in the bin.

These objects, and other advantageous ends which will be described hereinafter, I attain in the following manner, reference being had to the accompanying drawings in which—

Figure 1 is a side elevation of a separator, embodying my invention, showing it suspended from a conveyor pipe,

Figure 2 an end view of the same looking from the left of Figure 1,

Figure 3 a section on line 3—3 of Figure 2, and

Figure 4 a section on line 4—4 of Figure 3.

Referring to the drawings, the numeral

1 indicates a conveyor pipe having a discharge opening 2 adapted to be closed by a gate 3 which also serves to arrest the current of air through that part of the conveyor which is beyond the discharge opening. The separator is suspended from the conveyor pipe by pairs of arms 4 connected at their upper ends by bolts 5 extending transversely over the pipe. Below the pipe, arms 4 are connected by pairs of bars 6 and 7 parallel with the conveyor pipe. A frame member 8 is suspended between the lower pairs of bars 7, preferably about midway of their length. This frame member carries bearings 9 for the axle 10 of a cylinder 11 the periphery of which is composed of wire netting. The cylinder is provided at each end with a guide flange 12 which flares outwardly at an angle to the radii. Paddles 13, shown as four in number, extend between the flanges radially of the cylinder. For use the cylinder is positioned somewhat below the conveyor pipe and with its axis in range of the discharge but sufficiently beyond the discharge opening of the pipe to place the more remote or rear half of the cylinder out of range of the stock coming from the conveyor. A deflector 14 extends from frame member 8 to bars 6 and encloses the rear half of the cylinder except at the top and an opening 15 opposite the upper half of the cylinder for escape of air.

In operation the stock is blown against the upper front of the cylinder and falls upon one of the paddles. The cylinder rotates in anti-clockwise direction and the stock falls off. The natural path of the air current is through the cylinder to the deflector. Its force is partly dissipated by its impact with the exterior of the cylinder, the stock carried thereby and the paddles. Part of the air current passes through the cylinder and its force is dissipated to some extent by the interior wall of the cylinder and by the paddles and is deflected upwardly by the paddles. Any part of the current which may escape the cylinder and the paddles is arrested by the deflector. The air is free to escape in all directions except for the limited arc enclosed by the deflector and it is found by actual and continued use that the air through which the stock passes as it falls from the separator is in practical equilibrium and the stock falls in a conical pile without disturbance by the air. The result is a far more uniform mixture than could be at-

tained by the old plan and at far less expense.

While I have described my invention as taking a particular form, it will be understood that the various parts may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

- 15 1. An air separator for pneumatic conveyors including a rotatably mounted cylinder of wire netting adapted to be mounted below a discharge opening of the conveyor with its axis adjacent to and extending transversely of the path of the discharged material, whereby said material will fall onto and rotate the cylinder.
- 20 2. An air separator for pneumatic conveyors including a rotatably mounted cylinder of wire netting having a series of radially extending paddles and adapted to be mounted below a discharge opening of the conveyor with its axis adjacent to and extending transversely of the path of the discharged material, whereby said material will fall onto and rotate the cylinder.
- 25 3. An air separator for pneumatic conveyors including a rotatably mounted cylinder of wire netting having at each end a guide flange and adapted to be mounted below a discharge opening of the conveyor with its axis adjacent to and extending transversely of the path of the discharged material, whereby said material will fall onto and rotate the cylinder.
- 30 4. An air separator for pneumatic conveyors including a rotatably mounted cylinder of wire netting having at each end a guide flange and provided with a series of radial paddles extending between the guide flanges, and means for mounting the cylinder

der below a discharge opening of the conveyor with the axis of the cylinder adjacent to and extending transversely of the path of the discharged material, whereby said material will fall onto and rotate the cylinder.

5. An air separator for pneumatic conveyors including a rotatably mounted cylinder of wire netting adapted to be mounted below a discharge opening of the conveyor with its axis adjacent to and extending transversely of the path of the discharged material, whereby said material will fall onto and rotate the cylinder, and a deflector enclosing a substantial part of the rear half of the cylinder.

6. An air separator for pneumatic conveyors including a rotatably mounted cylinder of wire netting adapted to be mounted below a discharge opening of the conveyor with its axis adjacent to and extending transversely of the path of the discharged material, whereby said material will fall onto and rotate the cylinder, and a deflector enclosing a substantial part of the rear half of the cylinder, the deflector extending from a line vertically beneath the axis of the cylinder to a line above the body of the cylinder and having an opening in the rear of the upper half of the cylinder.

7. An air separator for pneumatic conveyors including a rotatably mounted cylinder of wire netting having at each end a guide flange and provided with a series of radial paddles extending between the guide flanges; a deflector enclosing a substantial part of the rear half of the cylinder, and means for mounting the cylinder below a discharge opening of the conveyor with the axis of the cylinder adjacent to and extending transversely of the path of the discharged material, whereby said material will fall onto and rotate the cylinder.

In testimony whereof I have signed my name to this specification.

WILLIAM S. SCHOFIELD.
